CLAIM

The ornamental design for a packing box, as shown and described.

DESCRIPTION

FIG. 1 is a front elevation view of a packing box, showing my new design, shown in a folded state and in use with environmental matter;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top, front and right perspective view thereof;

FIG. 8 is a top, front and right perspective view thereof, shown in a partially folded state; and,

FIG. 9 is a top plan view thereof, shown in an unfolded state. The long-broken lines in FIGS. 8 and 9 represent fold lines and are part of the claim. The short-broken lines illustrating the article in FIGS. 1, 3, 4, and 7 depict environmental subject matter that form no part of the claimed design; the other short-broken lines in the drawings illustrate portions of the packing box that form no part of the claimed design.
